UNITED STATES PATENT OFFICE.

JOHN S. PEARCE, OF VANCOUVER, BRITISH COLUMBIA, CANADA.

FURNACE.

Application filed July 19, 1923. Serial No. 652,589.

To all whom it may concern:

Be it known that I, JOHN S. PEARCE, citizen of the Dominion of Canada, residing at Vancouver, in the Province of British Columbia, Canada, have invented certain new and useful Improvements in Furnaces, of which the following is a specification.

This invention relates to a furnace for the efficient combustion of wood refuse or other fuel, such as low grade coal, lignite, peat or the like, which, for satisfactory consumption, require the delivery of air for combustion at various parts of the furnace or the combustion chamber. In order to effectively consume the gases as given off during the changing conditions of the fire level, and at the same time to deliver the products of combustion at a high temperature to the boiler or other purpose to which they are to be applied, the air delivery is dependent on the amount of fuel on the grate.

The feature of improvement in this invention to which attention is particularly directed lies in the means whereby the varying height and consequent condition of the fuel in the furnace chamber automatically regulates the flow of the furnace gases to suit the requirements of combustion under these changing conditions.

This result is attained by the use of a furnace chamber which is relatively deep and narrow and to this chamber air for combustion is delivered primarily through stepped grate bars, and secondarily through apertures in both side walls of the furnace chamber, which secondary supply of air is heated before delivery by its passage through the ducts in the walls of the furnace chamber. The hot gases from the furnace chamber are delivered from the back of the chamber through two exits, one approximately level with the grate bars and the other from the upper part of the chamber immediately over the first named exit, the upper exit delivering into the lower or direct exit approximate a third delivery of air to complete the combustion of the gases from the furnace.

The ports through which the secondary supply of air is delivered are so located that as the condition of the fire on the grate approaches its lower limit, they are partially uncovered, whereby the combustion of the incandescent fuel, being directly supplied with air, is intensified and the flame of this

rapid combustion passes through the upper exit and heats to a high temperature a mass of loosely stacked refractory material in the passage before it is delivered to the main or lower exit.

When the furnace is re-charged the volatile gases and vapours from the green fuel, as they pass through the highly heated upper exit, receive sufficient heat to be entirely consumed as they are delivered into the main exit.

The means by which these several results are attained is fully described in the following specification, reference being made to the drawings by which it is accompanied, in which:

Fig. 1 is a sectional plan showing the application of the furnace to the stack of a lime-kiln, being a section on the line 1—1 in Fig. 2.

Fig. 2 is a vertical section on the line 2—2 in Fig. 1, and

Fig. 3 is a vertical cross section on the line 3—3 in Fig. 1.

In these drawings 2 represents a deep and relatively narrow furnace chamber having stepped grate bars 3, a closable doorway 4 through which the fuel is charged and a closable door 5 affording access to below the grate.

From the back of this chamber 2 at the approximate level of the grate bars 3 a relatively large passage 6 delivers directly into the stack 7 of the lime-kiln, and from the upper part of the chamber 2 a smaller duct 8 delivers into a space 9 and therefrom through a duct 10 into the upper part of the direct passage 6. The space 9 is filled with loosely packed, refractory material, such as spaced apart fire-brick through which the gases are constrained to pass on their way to the direct passage 6.

A draw tunnel 11, closable at its upper end, affords access to the flue 6 for sampling the lime and for clearing away undue accumulation of lime from the flue.

Air for combustion is admitted through a pipe or duct 12 under control of a damper 13, and is delivered at 14 into the space below the grate and through branch ducts 15 in each side wall of the furnace to apertures located about level with the upper side of the direct passage 6, that is, slightly above the lower fuel line 16, (see Fig. 2). A duct 17, formed in the wall or floor of the furnace chamber, extends along below the draw

tunnel 11 through which duct air is delivered from the space below the grate into the outer end of the draw tunnel 11 and through it into the direct passage 6 from the furnace 5 to the kiln. In this duct 17 interspaced brick may be placed to more effectively heat the air passing through it.

Where the furnace is applied to a lime-kiln, as shown in the drawing, air is also 10 delivered through an aperture 18 into the kiln 7 immediately below the direct passage 6 from the furnace, which has the two-fold effect of cooling the burnt lime and supplying a supply of heated air to aid combustion 15 of gases in the kiln.

This threefold delivery of the air for combustion to below the grate at 14 into the combustion zone of the furnace through its side walls at 15, and through 17 and 11 into 20 the direct passage 6 from the furnace to the kiln, is productive of a favourable cycle of combustion which may be described as follows:

Assume the furnace to have been kindled 25 for a sufficient time to be in full working order, and that the fuel in the furnace chamber 2 has settled down, in a state of incandescence, to approximately the upper edge 30 of the direct passage 6 to the kiln. Under these conditions the secondary supply of air admitted through the ducts 15 in both side 35 walls of the furnace chamber considerably increases the combustion of the fuel in the space above it, the flame from which active combustion passes through the duct 8 from the upper part of this chamber and through the interspaced refractory material 9 and is 40 delivered through the duct 10 into the direct passage 6, to pass to the kiln with the gases drawn directly therethrough from the furnace and consumed with the hot air delivered into that passage through the draw tunnel 11.

The heat of this active combustion is imparted to the refractory material 9 through 45 the interspaces of which it has to pass.

Thereafter as the incandescent fuel sinks to the lower line 16, the furnace is recharged to the level of the full line 19. 50 When the fuel is filled to this line 19 entrance to direct passage 6 from the space above the fuel line is obstructed, and the volatile gases and vapours driven off from the green fuel must pass from the upper 55 part of the furnace chamber 2 through the duct 8 and through the interspaces of the refractory material 9, which has been highly heated by the previous passage of the flame through it. These highly heated unconsumed gases mixing with the third supply 60 of fresh heated air delivered through the draw tunnel 11 are effectively consumed before delivery to the kiln.

As the fuel 6 in the furnace chamber sinks, 65 the cycle above described is repeated.

The walls of the ducts 8, 9 and 10 are thus alternately highly heated by the flaming gases from the furnace when the fuel is incandescent and part with their heat to the cooler volatile gases when the furnace is 70 re-charged. This cycle, cooperative with the progress of combustion in the furnace chamber and the re-charging thereof is in a manner automatic and is favourable for satisfactory combustion under the changing 75 conditions of the fire, and particularly for the combustion of low grade fuels which are otherwise largely waste products, or which are difficult to find a market for.

The furnace chamber is made narrow and 80 deep to enable the heated air for combustion to be delivered effectively to the combustion zone of the fuel.

In applying this furnace to a stack lime-kiln, it is preferably applied in pairs, one 85 pair to each side of the kiln, and the space above the fuel line of each pair is connected together. That is, the partition wall between each pair is common to both, and the other pair of furnaces delivers into the opposite 90 side of the kiln 7.

It will be noticed that the hot gases from the furnaces are delivered at 6 into the stack 7 of the kiln at some little distance from the lower end through which the burnt lime is 95 withdrawn, so that as the lime is burnt it settles down below the passages through which the hot gases are delivered and has an opportunity to slowly cool before it is withdrawn through the drop door in the 100 bottom of the stack.

It will be further noticed that the air delivered at 18 to the kiln is relatively cool, so that the delivery of this supply of cool air, not only cools the burnt lime, but is 105 heated by contact therewith before it passes upward through the lime being burnt, where it is consumed and the heat of its combustion furthers the burning of the lime.

Although illustrated and described as applied to a lime-kiln, I do not desire to be confined to such use of the furnace, as the essential features of construction are applicable to any purpose where the nature of the fuel to be used will render it advantageous, for example, brick or pottery kilns, annealing ovens or steam generators, and although it may be used as a single furnace, it is preferable, owing to its relatively narrow width, to apply it in pairs.

Having now particularly described my invention, I hereby declare that what I claim as new and desire to be protected in by Letters Patent, is:

1. A furnace for the combustion of solid 125 fuel and the delivery of the hot gases therefrom, comprising a relatively deep and narrow chamber having walls of heat non-conducting material, a grate in the lower part of such chamber, a closable opening through 130

which the fuel may be delivered on the grate, a direct exit for the fuel gases adjacent the level of the grate, a second exit for the fuel gases delivering into the direct exit, means 5 for delivering air for combustion to below the grate, means for heating and delivering air through the side walls of the furnace adjacent the direct exit, and means for heating and delivering air into the direct exit adjacent 10 the connection of the second exit thereto.

2. A furnace for the combustion of solid fuel and the delivery of the hot gases therefrom, comprising a relatively deep and narrow chamber having walls of heat non-conducting material, a grate stepped downward 15

from the front toward the back, a closable opening through which fuel may be delivered on the grate, a direct exit for the fuel gases adjacent the level of the grate, a second exit for the fuel gases from the upper part of the chamber and delivering into the direct exit, means for delivering air for combustion to below the grate, means for heating and delivering air through the side walls of the furnace adjacent the direct exit, and means for heating and delivering air into the direct exit adjacent the connection of the second exit thereto.

In testimony whereof I affix my signature.

JOHN S. PEARCE.
